UNITED STATES PATENT OFFICE.

OSCAR L. SCALBOM, OF CHICAGO, ILLINOIS.

DIE-MAKER'S GAGE.

1,333,223.

Specification of Letters Patent.

Patented Mar. 9, 1920.

Application filed May 24, 1919. Serial No. 299,565.

To all whom it may concern:

Be it known that I, OSCAR L. SCALBOM, a citizen of the United States, residing at Chicago, in the county of Cook and State 5 of Illinois, have invented certain new and useful Improvements in Die-Makers' Gages, of which the following is a specification.

This invention relates to improvements in a die makers' gage particularly adapted 10 though not necessarily limited in its use, for transferring angles and obtaining the taper of holes, the inclination of surfaces, etc., and one of the objects of the invention is to provide an improved device of this character 15 embodying a freely adjustable narrow blade having a knife edge, and which device is so constructed and the blade is so attached thereto as to permit of a clear vision on both sides of the blade, thereby rendering it possible to permit of measurements 20 which cannot be made by the ordinary bevel protractor.

A further object is to provide an improved device of this character embodying 25 a blade adapted for adjustment throughout 360 degrees.

To the attainment of these ends and the accomplishment of other new and useful objects as will appear, the invention consists 30 in the features of novelty in substantially the construction, combination and arrangement of the several parts hereinafter more fully described and claimed and shown in the accompanying drawing illustrating 35 this invention and in which;

Figure 1 is a view in side elevation showing the manner of using the device for obtaining the taper of a die opening.

Fig. 2 is an end elevation.

Fig. 3 is a vertical longitudinal sectional view.

Fig. 4 is a detail perspective view of the blade.

Referring more particularly to the drawing the numeral 10 designates generally the body of the gage which may be of any desired size and is preferably rectangular in cross section. A portion of the lateral face 11 of the body is cut away or recessed as 45 at 12 to form a reduced portion 13, at the end of which reduced portion is a bearing 50

14, and which bearing is spaced from the shoulder 15 of the body formed by the cut away portion 12, and in a direction lengthwise of the body. A blade 16 which may 55 be constructed of any suitable material is provided preferably with a laterally projecting portion 17 at one extremity having an opening 18 therethrough. This blade may be of any desired length and is preferably 60 very thin or narrow having a knife edge 19, constituting the active edge of the blade. The blade is pivotally connected with the body portion 10 by means of a securing device 20 preferably in the form of 65 a thumb screw which passes through the opening 18 and into the bearing 14. The face of the bearing 14 is flush with the lateral face 11 of the body so that when the blade is secured to the body it is adapted 70 for free pivotal movement with respect to the body throughout 360 degrees and during such adjustment one of the faces of the blade 16 is adapted to pass over the lateral face 11 of the body.

It will be seen that with this construction, the blade during a portion of its adjustment will bridge or extend across the opening formed by the recess 12, thereby permitting a clear vision of both faces of 80 the active edge of the blade from behind the body.

This is particularly advantageous when measuring the inclination or taper of openings such as the opening 21 in a die 22. In 85 order to accomplish this the thumb screw 20 is loosened so as to permit of a free pivotal movement of the blade with respect to the body. The edge of the body 10 is then placed against the face of the die 22 90 with the blade 16 projecting into the opening 21. As soon as the knife edge 19 contacts with the face of the opening, the thumb screw may then be tightened to clasp the blade in a fixed position with relation to the 95 body 10. It will be seen that by the provision of the recess 12, a clear vision can be obtained on both sides of the knife edge 19 from behind the body portion 10.

This instrument is not only adapted for 100 measuring the taper of holes, but is also adapted for obtaining the angle of any sur-

face, which is facilitated by the clear vision of the blade and these angles which have been obtained, may be readily transferred.

5 While the preferred form of the invention has been herein shown and described, it is to be understood that many changes may be made in the details of construction and in the combination and arrangement of the 10 several parts, within the scope of the claims, without departing from the spirit of this invention.

What is claimed as new is:—

15 1. A die maker's gage embodying a body portion, a blade, means connecting the blade with the body portion for movement with respect thereto, the said means operating to secure the blade against movement with respect to the body, and means forming a 20 space intermediate the said body and the adjacent portion of the blade, whereby a clear vision of both sides of the blade may be had from behind the said body.

25 2. A die maker's gage embodying a body portion, a narrow blade connected with the body for movement with respect thereto, means operating to secure the blade against movement with respect to the body, the said blade having a knife edge extending lengthwise thereof, and means forming a space intermediate the said body and the adjacent 30 portion of the blade, whereby an unobstructed vision may be had throughout the entire length of the knife edge and on both sides thereof.

40 3. A die maker's gage embodying a body portion, a narrow blade connected by one end with the body for pivotal movement with respect to the body throughout 360 degrees, means securing the blade against pivotal movement with respect to the body, and means forming a space between the said body and the adjacent portion of the blade to provide a clear vision of both sides of the 45 active edge of the blade throughout the length thereof and from behind the said body portion.

50 4. A die maker's gage embodying a body portion, and a narrow blade connected by one end with the body for adjustment with respect thereto, a portion of the said body being cut away and recessed to form a sight opening in a direction lengthwise of the active edge of the blade, whereby a clear 55 vision may be had of both sides of the said edge.

5. A die maker's gage embodying a body portion, a blade connected by one end with the body for pivotal movement with respect 60 thereto, one face of said blade operating in a plane parallel with and in close proximity to a lateral face of the body portion, said body portion being provided with a recessed or cut away portion adjacent the pivot of the 65 blade and opening through the said lateral

face to provide a clear vision of the adjacent face of the active edge of the blade.

6. A die maker's gage embodying a body member, a portion of one lateral face being reduced in a direction transverse to said lateral face, a bearing carried by the reduced portion, the end of said bearing terminating in a plane substantially flush with the unreduced portion of the said lateral face, a blade pivotally connected with the said bearing, the inner face of said blade being movable over and in close proximity to said lateral face and bridging the space between the bearing and unreduced portion, whereby a clear vision may be had of both faces of the 80 active edge of said blade, and means securing the blade against pivotal movement with respect to the said body. 75

7. A die maker's gage embodying a body member, a portion of one lateral face being reduced in a direction transverse to said lateral face, a bearing carried by the reduced portion, the end of said bearing terminating in a plane substantially flush with the unreduced portion of the said lateral face, a 85 blade pivotally connected with the said bearing, the inner face of said blade being movable over and in close proximity to said lateral face and bridging the space between the bearing and unreduced portion, whereby a clear vision may be had of both faces of the 90 active edge of said blade, and means securing the blade against pivotal movement with respect to the said body, the said blade being adapted for pivotal movement throughout 95 360 degrees.

8. A die maker's gage embodying a body member, a portion of one lateral face being reduced in a direction transverse to said lateral face, a blade, a bearing at one end of the blade, said blade being movable over and in close proximity to the said lateral face of the body, a bearing disposed between one end of the blade and the said reduced portion of the body, means embodying said bearing for 105 securing the said end of the blade to the body for pivotal movement with respect thereto, whereby said blade will bridge the space between the bearing and the unreduced portion of the body to provide an unobstructed vision of both faces of the active 110 edge of the blade, the said blade being detachable from the said body. 115

9. A die maker's gage embodying a body member, a portion of one lateral face being reduced in a direction transverse to said lateral face, a blade, a bearing at one end of the blade, said blade being movable over and in close proximity to the said lateral face of the body, a bearing disposed between one end of the blade and the said reduced portion of the body, means embodying said bearing for 120 securing the said end of the blade to the body for pivotal movement with respect thereto, whereby said blade will bridge the 125 130

space between the bearing and the unreduced portion of the body to provide an unobstructed vision of both faces of the active edge of the blade, the said blade being detachable from the said body, the said securing means also operating to maintain the blade against pivotal movement and in

a fixed position with respect to the said body portion.

In testimony whereof I have signed my name to this specification on this 22nd day of May, A. D. 1919.

OSCAR L. SCALBOM.
